RADIO RECEIVER CABINET OR SIMILAR ARTICLE

Gordon L. Duern, Elmira, Ontario, Canada, assignor to
Electrohome Limited, Kitchener, Ontario, Canada

Continuation of design applications, Ser. No. 6,527, and
Ser. No. 6,537, Apr. 5, 1967. This application Mar. 22,
1968, Ser. No. 11,538

Term of patent 14 years

Int. Cl. D6—01

U.S. Cl. D56—4

FIG. 1

FIG. 2

FIG. 3

FIG. 4

FIG. 1 is a side and top perspective view of a radio receiver cabinet or similar article showing a first embodiment of my new design;

FIG. 2 is an opposite side and bottom perspective view of the radio receiver cabinet or similar article shown in FIG. 1;

FIG. 3 is a side and top perspective view of a radio receiver cabinet or similar article showing a second embodiment of my new design; and

FIG. 4 is an opposite side and bottom perspective view of the radio receiver cabinet or similar article shown in FIG. 3.

This application is a continuation of design applications Serial Nos. D-6,527 and D-6,537, both filed Apr. 5, 1967, both now abandoned.

The dominant features of my new design are shown in solid lines in the drawings.

I claim:

The ornamental design for a radio receiver cabinet or similar article, as shown and described.
